(57) **CLAIM**

We claim the ornamental design for a closure, as shown and described.

DESCRIPTION

FIG. 1 is a top perspective view of the claimed design showing the closure in an open configuration;

FIG. 2 is a bottom perspective view of the claimed design of FIG. 1;

FIG. 3 is a right side view of the claimed design of FIG. 1;

FIG. 4 is a left side view of the claimed design of FIG. 1;

FIG. 5 is a front view of the claimed design of FIG. 1;

FIG. 6 is a rear view of the claimed design of FIG. 1;

FIG. 7 is a top view of the claimed design of FIG. 1;

FIG. 8 is a bottom view of the claimed design of FIG. 1;

FIG. 9 is a top perspective view of claimed design of FIG. 1 showing the cap of the closure hinged at an angle relative to the base to the closure;

FIG. 10 is a top perspective view of the claimed design of FIG. 1 showing the closure in a closed configuration;

FIG. 11 is a bottom perspective view of the claimed design of FIG. 10;

FIG. 12 is a right side view of the claimed design of FIG. 10;

FIG. 13 is a left side view of the claimed design of FIG. 10;

FIG. 14 is a front view of the claimed design of FIG. 10; and,

FIG. 15 is a rear view of the claimed design of FIG. 10.

The broken lines are shown for the purpose of illustrating parts of the article that form no part of the claim.

1 Claim, 11 Drawing Sheets
